(57) **CLAIM**

The ornamental design for a peg system for humidor, as shown and described.

DESCRIPTION

FIG. 1 is a front perspective view of a peg system for humidor, illustrating our new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof; and,

FIG. 8 is another perspective view of the peg system for humidor shown in an environment of use. The broken lines in FIG. 8 are directed to environment that form no part of the claimed design.
